UNITED STATES PATENT OFFICE.

NEWELL SANDERS, OF CHATTANOOGA, TENNESSEE.

PLOW.

1,072,169.

Specification of Letters Patent.

Patented Sept. 2, 1913.

Application filed June 4, 1913. Serial No. 771,753.

To all whom it may concern:

Be it known that I, NEWELL SANDERS, citizen of the United States, residing at Chattanooga, Tennessee, have invented certain new and useful Improvements in Plows, of which the following is a specification.

My invention relates to gang plow frames of that class in which one main frame member is provided with a plurality of beams, each connected to the main frame member and carrying a furrow opening device. This construction is shown, among others, in Letters Patent of the United States, granted to me in 1903, and numbered 822,632. In this, as in my present invention, the furrow opening devices are in the form of disks.

My invention hereinafter described consists of a detail of construction in the disk carrying beams.

It is illustrated in the accompanying drawings, in which:—

Figure 1 shows in plan, the main frame member and beams of my improved plow; Fig. 2 illustrates the advantage of my improvement over the old form.

In plows of this class it is necessary that, in addition to the furrow opening devices, the front beam must carry the front supporting wheel, and that the rear beam must carry the rear supporting wheel and the plowman. This puts special strain upon these beams as compared with the intermediate beams and renders necessary a firmer connection with the main frame member by means of longer area of contact and more bolts. This increased firmness of attachment is amply provided for in the front beam, without change in its form, by mere extension as there is ample space at the front end of the main frame member for greater lap of the front beam and for more bolts than is necessary for the intermediate beams which carry only disks. For varying conditions it is necessary to expand and contract this arrangement of beams in order to cut either wide or narrow furrows, the minimum in usual practice being about six inches. In order to get the beams close enough together for this purpose, it is necessary to make a sharp angle where the beam leaves the main frame member, and it is also necessary that the front ends of all the beams, except the front beam, should be short, allowing for only two bolts on the usual size of main frame member. This allows the front end of the beam to go near

enough to the next beam ahead and also allows the forward end of the next beam behind to come up near enough to cut a minimum width of furrow. This shape of beam, however, does not admit of a longer bearing of rear beam upon the main frame member, which is necessary for requisite strength and does not admit of an increased number of bolts for the same purpose. I have found that I can accomplish this by extending the front part of the rear beam farther back, making a sharp angle or a short curve in order to bring the rear part of the rear beam in proper relation to the other beams, so that uniform furrows will be cut. This shape of beam cannot be used for the other beams of the plow, because this shape will not allow the next beam back to come up close enough in order to cut as narrow a furrow as is necessary.

Beams like the two front beams here shown are described in the patent above mentioned and have been in use for many years. The addition of the rear beam, of the shape shown, to this combination enables the plow to cut narrower furrows than before. For instance, with the usual size of material it was not possible to cut less than eight inch furrows before, while this arrangement makes it possible to cut six inch furrows.

Referring more particularly to the drawings, the main frame member is indicated at A. An intermediate beam which carries only a disk is marked b, and the rear beam, which carries, in addition to the ordinary disk, a supporting wheel and driver's seat, is marked b'. The straight part of the intermediate beam which bears upon and is bolted to the main beam, is marked 2. It is shortened, so that in its most advanced position (for the narrowest furrow) its forward end 3 abuts at the angle made by the next beam and the main frame member. But this length is sufficient for the bolts of the beams carrying only disks.

To give the greater bearing, the rear beam b' is formed with a single bend (omitting the straight middle part formerly used), as shown at 4. This is practically an extension rearward of the straight part of the beam which laps upon the main beam, and thus extended rearward it gives the needed increase in the bearing surface, and the space for increased number of bolts required for the greater strain. By reason also of the

more obtuse angle it brings the rear part of the beam and its disk into proper relation to the other beams and disks, and makes the furrows equal.

5 Fig. 1 shows the plow in its expanded form and Fig. 2 in its contracted form. It is plainly shown by the full lines that the forward or attaching part of the rear beam b' admits more bolts than the intermediate, 10 with the same spacing, though its front end abuts the bent portion of the preceding beam.

If the beam b' were of the old form with 15 two bends, with its attaching portion long enough for three bolts, as indicated in dotted lines, then it would not be possible to adjust it far enough forward by the space between 7 and 8 to bring its disk carrying portion in proper position.

In practice the number of bolts used is 20 limited by the space between them, on account of the space required for the nuts and a suitable wrench to turn them. The position of the bolt holes is indicated by the cross lines.

25

I claim as my invention:

In a gang plow of the class described, a main frame member, one or more beams having two bends or angles bolted thereto, and a rear beam having an extended part 30 lapped upon and bolted to said frame member and formed with a single bend.

In testimony whereof, I affix my signature in presence of two witnesses.

NEWELL SANDERS.
